(57) **CLAIM**

The ornamental design for a faceplate, as shown and described.

DESCRIPTION

FIG. 1 is a perspective view of a first embodiment for a face plate showing my new design;

FIG. 2 is a front side view of the faceplate of FIG. 1;

FIG. 3 is a left side view of the faceplate of FIG. 1;

FIG. 4 is a right side view of the faceplate of FIG. 1;

FIG. 5 is a top side view of the faceplate of FIG. 1;

FIG. 6 is a bottom side view of the faceplate of FIG. 1;

FIG. 7 is a perspective view of a second embodiment for a face plate of FIG. 1 with an inlay showing my new design; and,

FIG. 8 is an exploded view of the faceplate and inlay of FIG. 7.

The portions illustrated in broken lines on the figures are for illustrative purposes only and form no part of the claimed design.

1 Claim, 8 Drawing Sheets
